UNITED STATES PATENT OFFICE.

WILLIAM J. KELLEY, OF PITTSFIELD, ASSIGNOR TO THE SPRINGFIELD WOOD WORKING COMPANY, OF SPRINGFIELD, MASSACHUSETTS.

MOSAIC WOOD-WORK.

SPECIFICATION forming part of Letters Patent No. 392,810, dated November 13, 1888.

Application filed July 12, 1888. Serial No. 279,730. (No model.)

To all whom it may concern:

Be it known that I, WILLIAM J. KELLEY, of Pittsfield, in the county of Berkshire and State of Massachusetts, have invented a new and useful Improvement in the Manufacture of Mosaic Wood-Work, of which the following is a full, clear, and exact description.

This invention relates to an improvement in the mode of forming a mosaic flooring or wainscoting by first manufacturing composite strips having a facing of mosaic blocks, and then arranging such mosaic strips side by side upon the floor-base or wall in a manner to delineate the desired pattern.

This application relates more particularly to the mosaic strips as articles of manufacture, and to the mosaic flooring or wainscoting formed therefrom; and the invention, so far as this application is concerned, consists, primarily, of a mosaic strip, and, secondly, of a mosaic wood-work formed therefrom of novel form and construction, substantially as hereinafter particularly set forth, and as distinctly pointed out in the claims.

Reference is to be had to the accompanying drawings, forming a part of this specification, in which similar letters of reference indicate corresponding parts in all the figures.

Figure 1 is a plan view of a composite slab formed in the process of manufacturing my improved mosaic strips. Fig. 2 is an edge view of the said slab. Fig. 3 is a perspective view of one of the improved mosaic strips made from the slab. Fig. 4 is a plan view of an improved mosaic flooring formed from the said mosaic strips. Fig. 5 is a cross-section of the said flooring on the line *x x*, Fig. 4.

In manufacturing the improved mosaic strips A, thus illustrated, thin slightly-flexible sheets, as B, are sawed from some soft wood—for example, pine—in such a manner that the grain will run lengthwise thereof, as indicated in Fig. 1, and upon each sheet B are placed together, side by side, a series of vari-colored hard-wood facing-strips, C, the grain of successive ones of which is alternately crosswise of and in the direction of their length, in such a manner that the length of the strips C will be transverse to the grain of the wooden backing-sheet B. The bottoms only of the facing-strips are glued to

the backing-sheet B, the respective abutting side faces, D, of the strips C being left wholly detached, but brought into the necessary close relation with each other, before the glue is dried, by lateral pressure suitably applied to the outside strips, C. The composite slab thus formed and illustrated in Figs. 1 and 2 is, when fully dried, sawed through on lines F transverse to the length of the facing-strips C, and thus parallel to the grain of the wooden backing-sheet B, in such a manner as to make the composite strips A of a width equal to that of the original facing-strips C, and each consisting of a backing-strip, G, having a longitudinal grain and a single succession of vari-colored square facing-blocks, H, coincident in width therewith, having alternately a transverse and a longitudinal grain, their bottom faces firmly attached by the glue to the backing-strips G, but their respective abutting faces I disunited.

In applying the composite strips A to the formation of a mosaic flooring in the manner illustrated in Figs. 4 and 5, they are first run, like ordinary integral wooden strips, through a grooving-machine, whereby longitudinal grooves K are cut in the parts of their opposite side edges, formed by the corresponding edges of the series of facing-blocks H, and are then placed side by side on the floor-base L in such a manner that each block H will adjoin other blocks H, having a reverse grain thereto, and also the desired pattern be delineated. The respective abutting grooved side edges of the composite strips A are connected by longitudinal splines M, which are blind-nailed in the grooves and to the floor-base L in a manner common in laying plain board flooring, so that the backing-strips G, and hence the facing-blocks H, will be immovably secured to the floor-base or wall, while the said facing-blocks will be free to expand and contract in either direction independently of each other. The expansion or contraction being thus confined to each block, warping and opening of the face-joints will be prevented. This independence of the component blocks H is secured without the necessity of applying them singly to the floor-base, they being capable of being laid, as described, very readily and cheaply, and the stiffness of the wooden backing-strips G will too

cause them to bridge sudden inequalities in the floor-base, while their slight natural flexibility will permit them to conform to gradual variations in the level of the floor-base.

5 No claim is made in this application to the described process of manufacturing the mosaic strips, as the same is embodied in a separate application filed by me herewith.

Having thus described my invention, what I claim as new, and desire to secure by Letters Patent, is—

1. A mosaic flooring or wainscoting formed of a series of composite strips secured side by side to the floor-base or wall, each of said 15 composite strips being formed of a backing-strip of wood and a close succession of wooden facing-blocks glued at their bottoms to said

backing-strip, but wholly disunited at their respective abutting faces, and the respective abutting side edges of the composite strips being connected by spline and groove or kindred expansion joints, substantially as shown and described. 20

2. As an improved article of manufacture, a mosaic strip formed of a slightly-flexible integral wooden backing-strip and a single succession of abutting facing-blocks glued to said backing but detached from each other, and coincident in width with the backing strip, as and for the purpose specified. 25

WILLIAM J. KELLEY.
